UNITED STATES PATENT OFFICE.

STEPHEN A. TRAVERS, OF NEW YORK, N. Y., ASSIGNOR OF ONE-HALF TO JOHN F. KUHN, OF NEW YORK, N. Y.

GASOLENE AND OIL SEPARATOR.

1,105,223.

Specification of Letters Patent. Patented July 28, 1914.

Application filed May 4, 1914. Serial No. 836,197.

To all whom it may concern:

Be it known that I, STEPHEN A. TRAVERS, a citizen of the United States, and resident of the city of New York, in the county of Bronx and State of New York, have invented certain new and useful Improvements in Gasolene and Oil Separators, of which the following is a specification.

The present invention relates to an apparatus for separating gasolene, oil and the like from water, which is mixed therewith in cleaning and washing motor vehicles.

In washing motor vehicles in garages, they are usually placed upon the floor of the garage and a stream of water directed onto them for the purpose of removing dust, dirt, etc. The water is permitted to flow into the sewer, and obviously carries with it the gasolene and oil that has been removed in the process of cleaning from the motor vehicles, and so also the "drippings," that is to say the gasolene and oil that collects in drops on the floor while the vehicles are standing in the garage. It has been found lately that the gasolene so flowing into the sewer system collects in the sewer, resulting in frequent explosions, which are dangerous for the reason that they are apt to seriously interfere with the proper operation of the sewer system, and drive the covers of the manholes of the sewers out of place.

One of the objects of the present invention is to provide a gasolene and oil separator which is inserted into the pipe leading to the sewer, and effectively prevents the flowing of the gasolene, oil and the like into the sewer system.

Another object of the invention is to combine with the separator a mechanism which catches the sand, mud, etc., from the water as the same flows through the separator into the sewer, in order to prevent a clogging of the pipe leading to the sewer.

A further object of the invention is to produce a separator of the character described that can be manufactured on a commercial scale, or in other words one which is so simple to construct as not to be beyond the reasonable cost of such a contrivance.

With these and other objects in view, which will more fully appear as the nature of the invention is better understood, the same consists in the combination, arrangement and construction of parts hereinafter fully described, pointed out in the appended

claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawing which is a front elevation of an apparatus constructed in accordance with the present invention.

In the drawing, the numeral 10 indicates a closed metallic receptacle, preferably cylindrical in shape. This receptacle may be supported in any suitable manner. Near its top this receptacle is provided with an inlet opening 11, to which leads a supply pipe 12, into which is inserted a valve 13 of any suitable construction to control the flow of the liquid into the receptacle. This supply pipe extends into the receptacle and is bent in the longitudinal axis thereof downward, as clearly shown at 14. From the supply pipe 12 is suspended a bell-shaped deflector 15, said deflector being disposed a little distance below the outlet or discharge mouth of the supply pipe in the longitudinal axis of said receptacle, for a purpose hereinafter to be described. Below the receptacle 10 is located a container 16 of any suitable shape, said container being connected by a pipe 17 with the receptacle 10, the pipe 17 leading from the bottom of the receptacle to the top of the container. From the top of the container extends upwardly in a vertical direction a pipe 18, that is connected in any suitable manner a substantial distance below the level of the top of the receptacle 10 with a substantially horizontally extending pipe 19 that leads to the sewer. The container 16 is provided with a hand-hole 20, that is normally closed by a cover 21, its purpose being

to permit the removal of the solid matter that collects in the container. Near its top the container 16 is provided with a drain cock 22, through which the contents of the receptacle 10 may be removed before the container 16 is being cleaned.

The top of the receptacle 10 is provided with an air-vent 23, to prevent the formation of an air-cushion in the said receptacle.

In the side of the receptacle 10 is provided a sight-opening 24, that is covered

by a glass plate 25, the latter being held in place in any suitable manner. Through this sight-opening the upper level of the water and consequently the lower level of the gasoline and the like separated therefrom may be viewed. In the side of the receptacle are also formed a plurality of outlets 26, said outlets being disposed in different horizontal planes, and connected by pipes 27 with a discharge pipe 28. In each of the pipes 27 is inserted a valve 29.

The operation of this device is as follows: The supply pipe 12 is connected with the cesspool of the garage and the pipe 19 with the sewer, the entire apparatus being located below the level of the floor of the garage, and forming thus a trap that seals the sewer against a return flow. Normally the valve 13 is open, the drain cock 22 and the valves 29 being closed. The device is first given an initial charge of clean water. The mixture of water, gasoline, oil and the like enters through the supply pipe 12 the receptacle 10, where its flow is substantially retarded as the mixture is deflected and spread by the bell-shaped deflector 15. This deflector, retarding the flow of the liquid and spreading it over substantially the entire area of the receptacle 10, serves to prevent a churning of the liquid in the receptacle, thereby permitting the gasoline, oil and the like to separate from the water and to rest on top of the water. Any air under compression in the receptacle 10 escapes through the vent 23. The water from which the gasoline and the like has been separated flows into the container 16, where sand and other solid matter settles onto the bottom. From the container 16 the water flows through the pipes 18 and 19 into the sewer. The lower level of the gasoline and the like is viewed through the sight-hole 24 in the receptacle. Whenever it is intended to discharge the gasoline from the receptacle, that valve 29 is opened below the level of which the lower gasoline level is located. In opening the said valve, the gasoline and the like is run from the receptacle through the corresponding pipe 27 into the discharge pipe 28, below which a vessel is placed to collect the said gasoline.

With the herein described construction a complete separation of the gasoline and the like is insured, as any gasoline or the like that may be entrained with the water sepa-

rates from the latter, inasmuch as the flow of the liquid in the receptacle is materially retarded and the liquid in the receptacle is not stirred up or agitated by the inflowing liquid, due to the operation of the deflector 15.

It is to be observed that, inasmuch as the receptacle 10 with the container 16 and the pipe 18 connected therewith forms a U-shaped passage that is inserted into the sewer system, the apparatus serves at the same time as a trap which prevents a return flow of liquid and of obnoxious gases, etc. into the garage.

What I claim is:—

1. In a gasoline separator, the combination with a closed receptacle for the liquid to be treated, of a container disposed below said receptacle and communicating therewith, a supply pipe leading into said receptacle near its top provided in the longitudinal axis of said receptacle with a downwardly pointing bend, flow retarding and deflecting means in said receptacle below the mouth of said bend, a discharge pipe connected with said container extending upward in parallel relation to said receptacle, said receptacle being provided with a plurality of outlets that are disposed in different horizontal planes, and means for controlling independently of each other said outlets.

2. In a gasoline separator, the combination with a closed receptacle for the liquid to be treated, of a container disposed below said receptacle and communicating therewith, a supply pipe leading into said receptacle near its top provided in the longitudinal axis of said receptacle with a downwardly pointing bend, a bell-shaped deflector in said receptacle below the mouth of said bend, a discharge pipe connected with said container extending upward in parallel relation to said receptacle, said receptacle being provided with a plurality of outlets that are disposed in different horizontal planes, and means for controlling independently of each other said outlets.

Signed at New York, in the county of New York, and State of New York, this 28th day of April, A. D. 1914.

STEPHEN A. TRAVERS.
